CLAIM

The ornamental design for a tire tread for a vehicle tire, as shown and described.

DESCRIPTION

FIG. 1 is a perspective view of the vehicle tire, showing my new design;

FIG. 2 is a front elevational view thereof; and

FIG. 3 is a left side, elevational view thereof;

FIG. 4 is a right side, elevational view thereof; and,

FIG. 5 is a partial front view thereof, illustrated on a larger scale.

The tire tread pattern is repeated uniformly around the circumference of the tire. The dash-dot lines showing the boundaries of the claim and the broken lines depicting unclaimed subject matter do not form a part of the claim.
